UNITED STATES PATENT OFFICE.

PAUL T. FIEHLER, OF GORDONVILLE, MISSOURI.

NUT-LOCK.

1,071,635.

Specification of Letters Patent. Patented Aug. 26, 1913.

Application filed April 26, 1913. Serial No. 763,867.

To all whom it may concern:

Be it known that I, PAUL T. FIEHLER, a citizen of the United States, residing at Gordonville, in the county of Cape Girardeau and State of Missouri, have invented 5 certain new and useful Improvements in Nut-Locks, of which the following is a specification, reference being had to the accompanying drawings.

10 This invention relates to new and useful improvements in nut locks and more particularly to a lock adapted for application to a rail joint and the like, the object of the invention being to provide a nut lock of the 15 above character which will lock a plurality of nuts against rotation thus materially assisting in securely holding the fish plates upon a rail joint in their operative position.

Another object of the invention is to provide 20 a nut lock of the above character which will possess advantages in points of efficiency and durability, is inexpensive of manufacture and at the same time is simple in construction and operation.

25 With the above and other objects in view, this invention consists in the novel features of construction and the combination and arrangement of parts to be hereinafter more fully described, pointed out in the claim and 30 shown in the accompanying drawings, in which—

Figure 1 is a side elevation of a nut locking device constructed in accordance with my invention; Fig. 2 is a horizontal sectional view; Fig. 3 is a detail perspective view of one end of the bearing plate; Fig. 4 is a detail perspective view of one end of the locking plate; and Fig. 5 is a detail enlarged sectional view illustrating the relative 35 position of the reinforcing members with respect to the nuts.

Referring more particularly to the drawings, 1 and 2 indicate the meeting ends of two rails which are held against lateral 45 movement by the rail chair 3, the vertical spaced uprights of said chair being securely fastened to the rails 1 and 2 by means of the bolts 4, said bolts having nuts 5 upon one end thereof to hold the same in their operative 50 position. These nuts 5 are securely held against rotary movement through the medium of a plate 6 which is mounted upon the bolts 4 and disposed between the nuts and the side portions of the rail chair 3. 55 The plate 6 is provided at each end thereof with a loop 7, said collars projecting through

the openings 8 formed in the locking plate 9. Securing pins 10 are inserted within the loops 7 after the locking plate has been placed in position to securely hold said locking plate against longitudinal movement. 60

The locking plate 9 is provided with a plurality of openings 11 which are adapted to receive the nuts 5 threaded upon the outer ends of the bolts 4 to hold the same against rotary movement. The material which is cut from the openings 11 is bent back in opposite directions so as to reinforce the edges of the openings and adapted to engage the sides of the nuts 5 to securely hold them 70 against rotary movement. It will be apparent that by forming the openings 11, the side edges of the same, as shown at 12 and 13, are cut. The central portion of the material is then split in half and each half 75 of the material formed by cutting the opening, is bent in opposite directions and curved upon itself, as shown at 14, to engage opposite sides of the nut. From this it will be seen that in securely locking the nuts 5 80 against rotation, the plate 6 is placed upon the bolts and locked in position by threading the nuts 5 upon the outer ends of the bolts. The locking plate 9 is then engaged over the nuts, the loops 7 project through the 85 openings 8 in said plate and having the pins 10 inserted therethrough to securely hold the plate against lateral movement, it being understood that the nuts 5 will hold the plate against longitudinal movement. 90

From this it will be apparent that I have provided a simple and durable nut locking device which is particularly adapted for locking nuts upon rail joints and the like and which at the same time will securely 95 lock a plurality of nuts against rotation. It will also be apparent that my device is extremely simple in construction and can be manufactured at a comparatively low cost.

While I have shown and described the 100 preferred form of my invention, it will be obvious that various changes in the details of construction and in the proportions may be resorted to for successfully carrying my invention into practice without sacrificing 105 any of the novel features or departing from the scope of the appended claim.

What I claim is:—

The combination with a rail joint and the fish plate and locking bolts having nuts on 110 one end thereof, of a plate mounted upon said bolts and disposed between the nuts and

fish plate, loops formed upon each end of said plate, a locking plate having openings through which said loops are disposed, pins inserted through said loops to hold said plates in their locked position, said locking plate being provided with openings and the material cut from said openings being curved in opposite directions upon the side edges of the openings to reinforce the same

and engage the sides of the nuts to prevent rotation of the same.

In testimony whereof I hereunto affix my signature in the presence of two witnesses.

PAUL T. FIEHLER.
